The ornamental design for a vacuum cleaner brush attachment, as shown and described.

DESCRIPTION

FIG. 1 is a perspective view of a vacuum cleaner brush attachment showing my new design.

FIG. 2 is another perspective view thereof;

FIG. 3 is another perspective view thereof;

FIG. 4 is another perspective view thereof;

FIG. 5 is another perspective view thereof;

FIG. 6 is a side view thereof, the opposite side view being a mirror image.

FIG. 7 is a front view thereof.

FIG. 8 is a rear view thereof.

FIG. 9 is a top view thereof; and,

FIG. 10 is a bottom view thereof.

The broken lines shown in the drawings are included for the purpose of illustrating environmental structure and form no part of the claimed design.
